Primary Examiner — Leanne Was-Englehart(74) Attorney, Agent, or Firm — McHale & Slavin, P.A.(57) CLAIM

The ornamental design for a panel, as shown and described.

DESCRIPTION

FIG. 1 is a top left front perspective view of the panel of the present invention;

FIG. 2 is a front view thereof;

FIG. 3 is a top view thereof;

FIG. 4 is a left side view thereof; and,

FIG. 5 is a right side view thereof.

The portions of the panel illustrated in broken lines form no part of the claimed design.

1 Claim, 4 Drawing Sheets(56)
